UNITED STATES PATENT OFFICE.

RUDOLPH GNICHWITZ, OF ASHBOURNE, ASSIGNOR TO THE MATHER MANUFACTURING COMPANY, OF PHILADELPHIA, PENNSYLVANIA.

DESIGN FOR A FONT OF PRINTING-TYPE.

SPECIFICATION forming part of Design No. 20,417, dated December 16, 1890.

Application filed November 24, 1890. Serial No. 372,585. Term of patent 3½ years.

To all whom it may concern:

Be it known that I, RUDOLPH GNICHWITZ, a citizen of the United States, residing at Ashbourne, in the county of Montgomery and State of Pennsylvania, have invented a certain new and useful Design for a Font of Printing-Type, of which the following is a full, clear, and exact description.

The leading features of this design for a font of printing-type are the outline scroll-formed Italic capitals and lower-case letters and other characters, the closed-point terminals of all the letters and characters, the open swell formed of double lines at top and bottom of all the characters, and the fine single connecting-lines in the center of all the characters, all combined to produce the several configurations of the characters, as shown in the accompanying illustrations.

The font includes capitals, lower-case, nu-

merals, punctuation-marks, and the other usual characters going to make up a font of type, each and all of which are of substantially the shape and configuration shown in the annexed drawing or illustration.

The main characteristic of the design may be stated to be an Italic character constructed in outlines, with the shading at top and bottom.

What I claim is—

The design for a font of printing-type, substantially as shown and described.

In testimony whereof I have hereunto set my hand this 22d day of November, A. D. 1890.

RUDOLPH GNICHWITZ.
